KARL FREY, OF ENNETBADEN, SWITZERLAND, ASSIGNOR TO AKTIENGESELLSCHAFT BROWN BOVERI & CIE., OF BADEN, SWITZERLAND, A JOINT-STOCK COMPANY OF SWITZERLAND.

TURBINE CONSTRUCTION.

Application filed July 7, 1927, Serial No. 204,120, and in Germany July 12, 1926.

This invention relates to steam turbine construction, particularly to turbines of the double flow type, which are characterized by arrangement of separate steam cylinders in the same casing, the steam flowing in opposite directions through the different cylinders.

The object of the present invention is the provision of a construction whereby the turbine is adapted for operation with economical steam consumption at reduced loads, as well as a full load, without disturbing the thrust balance on the shaft, irrespective of which section is being employed.

Another object is the provision of a construction which will accomplish these results and prevent overheating in the section which is not under steam.

Other and further objects will be pointed out or indicated hereinafter upon an understanding of the invention or its employment in practice.

In the drawing forming a part of this specification

Fig. 1 is a diagrammatic illustration in the nature of a sectional elevation of a double flow turbine embodying the invention;

Fig. 2 is a detail in the nature of a longitudinal section through a portion of the thrust compensating device and adjacent blade carrying portions;

Fig. 3 is a section similar to Fig. 2 but showing a modified form of construction for the thrust compensating device, and

Fig. 4 is a diagram illustrating the relationship of blading in the form illustrated in Fig. 3.

It is to be understood that while the constructions here illustrated are presented as examples of structure in which the invention may be embodied, the invention is susceptible of incorporation in various other forms differing from these, but still within the spirit and scope of the appended claims.

In the operation of reaction turbines of the double flow type, an undesirably high steam consumption takes place if operating steam is admitted to both sections, when on reduced loads. Moreover, in turbine installations containing a number of units, and where the load fluctuates between wide limits, it is a fact of experience that on the lower fractional loads large differences appear in the percentage loads taken by the individual units. This may be a great disadvantage under cer-

tain circumstances, for example, when a number of machines of a similar type are being driven, and it is necessary, when the total load falls, that the loads carried individually by the several units should be reduced in approximately the same proportion. Such a case arises, for example, when a number of screw propellers of a vessel are driven by associated turbine sections, or when a number of separate turbines deliver power to a single gear. The present invention relates to a construction for turbines of the double flow type, in which the axial thrust on the shaft is balanced, and one of the sections may be cut out completely, for reduction of load without disturbing the thrust balance.

As illustrated in the accompanying drawing, the casing is constructed so as to afford two operating cylinders or turbine sections 10 and 11 to which steam admission is had separately from admission chambers 12 and 15 at the mid-portion of the casing, the steam flowing in opposite directions through the different cylinders to the exhaust chambers 14 and 17. Admission to chamber 12 is controlled by valve 16, and to chamber 15 by valve 19. The rotor drums 18 and 21 for the respective cylinders are carried on the same shaft 20 and the blading 22 and 25 in both sections is arranged to actuate the drums and shaft in the same direction. Between the two sections, the shaft carries a dummy piston 24 upon which the steam pressure in either section is effective to counterbalance the axial thrust on the rotor blades. In the form illustrated in Fig. 2, a seal is provided across the dummy piston by labyrinth elements 26, so as to control the leakage of steam from one cylinder to the other. When the turbine is required to work against a very high back pressure, however, and a substantial amount of steam flow through the non-working cylinder must be permitted, in order to avoid excessive windage losses and heating, a construction such as that illustrated in Figs. 3 and 4 is employed. In this arrangement, the flow control across the dummy piston is accomplished by the use of a series of small auxiliary blades 27 mounted in cooperating relationship on the dummy piston 24 and on the associated portion of the casing, said blades being arranged to permit passage of steam from the working cylinder to the cylinder which is cut out when op-

erating at reduced load. With proper proportion and design, either the labyrinth or the auxiliary blade arrangement may be constructed so that the leakage from the working cylinder to the non-working cylinder is just sufficient to cover the losses of the otherwise empty blading of the latter. In the construction illustrated in Figs. 3 and 4, the arrangement is such that the direction of flow of steam through the auxiliary blades 27 is from the chamber 12 to the chamber 15.

In operation at full load, steam is admitted to both cylinders through the valves 16 and 19. At reduced load, however, one or the other of the cylinders may be cut out of operation by the closing of its valve. Under either condition of operation, the axial thrust of the rotor blades is balanced by the thrust on the cylinder 24. With either of the constructions illustrated in Figs. 2 and 3, the leakage across the dummy piston is adequate to supply the losses of the non-working cylinder, which, in the arrangement illustrated in Figs. 3 and 4 will be the cylinder 11.

This invention is of greatest utility in installations in which high boiler pressures are employed and the turbine works against a considerable back pressure.

What I claim is:

1. In a steam turbine of the double flow type, in combination, a casing affording re-

spective working cylinders arranged to transmit steam in different axial directions, a common shaft served by said cylinders, blading in the cylinders arranged to induce rotation of the shaft in the same direction, means for controlling steam admission to different cylinders independently, a thrust balancing element carried by the shaft and subject to pressure of steam in different cylinders, and auxiliary blading carried by said element for controlling the flow of steam from one cylinder to another.

2. In a turbine of the double flow type, in combination, a casing affording respective working cylinders with respective admission chambers at their adjacent ends and exhaust chambers at their remote ends, means for controlling steam admission to the admission chambers respectively, a common shaft served by both cylinders, blading in the cylinders arranged to actuate the shaft in the same direction, a thrust balancing element carried by the shaft and subject to pressure of steam from both admission chambers, and auxiliary blading associated with said element for controlling passage of steam from one cylinder to the other.

In testimony whereof I have hereunto subscribed my name this 24th day of June A. D. 1927, at Zurich, Switzerland.

KARL FREY.
